ATTORNEY

UNITED STATES PATENT OFFICE

170,902

NEWSPAPER AND PERIODICAL HOLDER
OR SIMILAR ARTICLE

Saul K. Wolff, Long Beach, N. Y.

Application August 21, 1953, Serial No. 26,540

Term of patent 14 years

(Cl. D33—2)

To all whom it may concern:

Be it known that I, Saul K. Wolff, have invented a new, original, and ornamental Design for a Newspaper and Periodical Holder or Similar Article, of which the following is a specification, reference being had to the accompanying drawing, forming a part hereof.

Fig. 1 is a perspective view of a newspaper and periodical holder or similar article, showing my new design.

Fig. 2 is a side view thereof.

I claim:

The ornamental design for a newspaper and periodical holder or similar article, as shown.
SAUL K. WOLFF.
